DENTAL COMPACT OR TOOTHBRUSH KIT

Elizabeth E. Smith and Will O. Smith, Pittsburgh, Pa.

Application July 11, 1955, Serial No. 521,198

3 Claims. (Cl. 132—84)

This invention relates to a toothbrush kit or dental compact. 15

This invention is an improvement over the toothbrush kit shown and described in our prior patents such as Patent No. 2,476,686.

The object of the invention is to provide a toothbrush kit which is constructed so that the toothbrush will be held immobile in its various adjusted positions, and wherein the brush can be readily moved into engagement with the dentifrice in the container.

Another object of the invention is to provide a dental compact which is adapted to be folded so that it occupies a minimum amount of space when it is not being used, and wherein the compact includes a compartment or container for holding a quantity of dentifrice, and whereby there is provided a toothbrush which can be readily moved into engagement with the dentifrice when the dentifrice is to be placed on the toothbrush bristles, and whereby the brush can be readily moved to an extended position when the teeth are to be brushed.

A further object of the invention is to provide a dental compact which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a perspective view of the dental compact, showing the parts in open position and with the toothbrush extended.

Figure 2 is a longitudinal sectional view taken through the dental compact, and showing an intermediate position of the toothbrush.

Figure 3 is a longitudinal sectional view taken through the compact, showing the parts in closed position.

Figure 4 is a fragmentary sectional view showing the parts separated.

Figure 5 is a sectional view taken on the line 5—5 of Figure 4.

Figure 6 is a view similar to Figure 5, but showing the collar shifted.

Figure 7 is a perspective view illustrating the collar, casing, clip, and a portion of the toothbrush handle.

Figure 8 is an end elevational view illustrating the collar in closed position.

Figure 9 is an end elevational view illustrating the collar in open position, and with the handle of the toothbrush shown in section.

Figure 10 is a perspective view of the clip.

Referring in detail to the drawings, the numeral 10 designates a housing which includes a substantially cylindrical side wall 11. An end wall 12 closes one end of the housing 10, while the other end of the housing 10 is open. Projecting inwardly from the end wall 12 and secured thereto or formed integral therewith is a cylindrical flange 14 which coats with the side wall 11 of the housing 10 to define a recess 15. The wall 11 of the

2

housing 10 is further provided with an elongated cutout 16, and there is provided in the wall 11 an arcuate groove or channel 17 for a purpose to be later described.

There is further provided a hollow casing 18 which has a substantially cylindrical shape, and the casing 18 includes a curved side section 19 which is provided with a longitudinally extending cutout that includes an enlarged portion 20 and a smaller portion 21. A curved tongue or rib 22 extends outwardly from the section 19 of the casing 18, and the tongue 22 is adapted to travel or ride in the groove 17.

A clip or bracket 23 is provided with notches 24, Figure 10, and a toothbrush 25 includes a handle 26 which is provided with lugs 27 that are detachably mounted in the notches 24 in the clip 23. The clip 23 is slidably mounted in a channel or trackway 28 which is defined by a wall portion 29 and the adjacent parts of the casing. The toothbrush 25 is provided with the usual bristles 30 for engagement with a person's teeth.

Slidably connected to the casing 18 is a container or compartment 31 which includes a side wall portion 32 and end wall portions 33 and 34. A finger engaging lug 35 extends upwardly from the wall portion 34, whereby the finger of a person can be arranged in engagement with the lug 35 when the container 31 is to be moved to the open position shown in Figure 2 or to the closed position shown in Figures 3 and 4.

There is further provided a collar 36 which is rotatably mounted on an end of the casing 18, and the collar 36 includes a cylindrical portion 37 and an end portion 38. The cylindrical portion 37 of the collar 36 is provided with a split 39, and the end portion 38 is provided with a cutout or arcuate slit 40. The collar 36 may be provided with exteriorly arranged knurling or roughened surfaces 41 so as to facilitate the manual rotation of the collar 36.

From the foregoing, it is apparent that there has been provided a dental compact which is an improvement over the dental compact shown in our prior patents such as prior Patent No. 2,476,686. In use, the container 31 may be filled with powder or other dentifrice or tooth cleaning composition, and the parts may be assembled as shown in the drawings. When the dentifrice is to be arranged on the bristles 30 of the toothbrush 25, the finger can be arranged in engagement with the lug 35 to extend the container 31 to the position shown in Figure 2. Then, the brush 25 can be pivoted about an axis extending through the lugs 27 so that the bristles 40 can be moved into engagement with the dentifrice in the container 31.

After a sufficient quantity of dentifrice has been picked up by the bristles 30, the container 31 can be moved back to its position within the casing 18 as shown in Figure 4. The clip 23 is slidably mounted in the channel 28. The brush clip rides on the cover of the dentifrice container. To remove the brush as when a new brush is to be inserted, the brush clip is brought back far enough for clearance to permit removal of the brush. The clip remains in slidable position at all times since it can not pass the dentifrice container lug unless the drawer is pulled to open position. If desired, the toothbrush 25 can be moved to the extended position shown in Figure 1 after the dentifrice has been arranged on the bristles 30 so that the teeth can be readily brushed. Thus, when the brush 25 is being moved to the position shown in Figure 1, the collar 36 is rotated so that its slot 39 registers with the slot 21 in the casing 18. Then, after the brush 25 has been moved to its extended position, the collar 36 is rotated so that the slot 39 in the collar moves out of registry with the slot 21 whereby the handle 26 of the toothbrush will project through the cutout 40 in the collar and the toothbrush will thus be locked in its extended position.

Due to the provision of the curved track 17 and curved

tongue 22, the housing 10 will move into closing relation with respect to the casing 18 when the parts are moved to the closed position shown in Figure 3. Thus, by simply manually rotating these parts, the trackway will insure that when open the cutout 16 in the housing 10 registers with the cutout 20 in the casing 18 so that the container 31 can be readily moved to its open position to permit the toothbrush to pick up tooth powder. The recess 15 receives the end of the casing 18 when the device is in closed position.

With the present invention, the bristles 30 can be dipped into the entire area of the container 31.

We claim:

1. In a dental compact, an outer housing including a cylindrical side wall provided with an elongated cutout and a circular end wall closing one end of said housing, the other end of said housing being open, a circular flange extending inwardly from said end wall and coacting with said side wall to define a recess, there being a curved groove arranged in the side wall of said housing intermediate the ends thereof, a casing movably mounted in said housing and including a curved side section provided with an arcuate tongue for travel in the groove in said housing, said casing further including a section coacting with a portion of said housing to define a trackway, a clip slidably mounted in said trackway, a toothbrush including a handle detachably and pivotally connected to said clip, and a split collar rotatably connected to said casing for

selective engagement with the handle of the toothbrush, there being an enlarged cutout in said casing communicating with an elongated cutout of smaller size, said split collar including a cylindrical portion provided with a slot mounted for movement into and out of registry with the cutout in said casing, said split collar further including an end portion provided with an arcuate slit for the projection therethrough of a portion of the toothbrush handle whereby when the slot in the collar moves out of registry with the cutout in the casing and with the handle of the toothbrush projecting through the slit in the collar, the toothbrush will be locked in its extended position.

2. The structure as defined in claim 1, wherein said clip is provided with notches, and lugs on said toothbrush for engagement with said notches.

3. The structure as defined in claim 1, and further including a container for holding dentrifice slidably mounted in said casing, said container including a side wall having an opening therein, and end walls extending upwardly from the side wall of said container, and a finger engaging lug on said container.
